UNITED STATES PATENT OFFICE.

JAMES H. QUINN, OF BROOKLYN, NEW YORK.

NON-REFILLABLE BOTTLE.

No. 893,651.

Specification of Letters Patent.

Patented July 21, 1908.

Application filed August 9, 1907. Serial No. 387,856.

To all whom it may concern:

Be it known that I, JAMES H. QUINN, a citizen of the United States, residing at Brooklyn, in the county of Kings and State 5 of New York, have invented a new and useful Improvement in Non-Refillable Bottles, of which the following is a specification.

This invention relates to a non-refillable bottle, and has for its object the overcoming 10 of the defects common with many bottles popularly supposed to be non-refillable bottles but which, in fact, can be refilled if submerged in a liquid in an inverted position. I avoid these difficulties by a double ball 15 valve, one of said balls being of a light material and acting both as a valve and a float and the second being of metal and rolling freely upon the first mentioned ball when the bottle is in an upright position thus securely 20 holding it to its seat and preventing it from becoming unseated by pouring liquid into the bottle when in an upright position.

The invention consists essentially in a float valve, a ball weight coöperating with 25 said float valve and a suitable retaining device for holding the balls.

In the accompanying drawings, Figure 1 is 30 a sectional view through the neck of a bottle and through my device, the balls being shown in elevation and in the position occupied when the bottle is in an upright position. Fig. 2 is a similar view showing the position occupied by the balls when the bottle is gently decanted. Fig. 3 is a detail perspective view of the retaining cage removed 35 from the bottle, and Fig. 4 is a section on the line 4—4 of Fig. 1.

In the drawings A represents the upper portion of a bottle having an elongated neck 40 portion A' slightly contracted in its lower portion and provided with an annular roll A² adjacent its upper end above which a cork or stopper of any kind not shown can be inserted. The retaining device consists of a cylinder B 45 having a lower truncated conical portion B' upon which is fitted a rubber collar C which wedges into the contracted portion of the bottle neck and thus preventing the passage of any liquid from or into the bottle between 50 the sides of the bottle neck and the retaining device. The cylinder B is held in the neck of the bottle against withdrawal by two angle spring arms D which are secured to the sides of the cylinder and which spring outwardly 55 as their angle portions pass the shoulder A² and engage the said shoulder. To prevent

any tampering with the valves by the insertion of a wire or other instrument a suitable valve cage E having a slotted top portion and side openings is secured in the upper portion 60 of the cylinder B, and the free ends of the spring arms D project into and rest beneath the top of said cage, thereby preventing their being engaged by a hook or gripping device and drawn upwardly for the purpose of dis- 65 engaging them from the shoulder A². The valves are further held in place by two cross bars F arranged one above the other and at right angles to each other, these bars extending diametrically across the cylinder B. I 70 also place within the cylinder B a tapering sleeve G with its smaller end downward and the upper end portion longitudinally slit. The sleeve is of a spring metal and its lower portion is of less diameter exteriorly than the 75 interior diameter of the cylinder B while the diameter of its upper portion is slightly greater. By forming it of spring metal and slitting the upper portion, it can be readily forced into the cylinder B and the lower portion 80 will stand out spaced from the sides of said cylinder as shown in the drawings. The lower edge of this sleeve acts as a stop for one of the ball valves as will hereafter appear.

Within the conical portion of the cylinder 85 B, I place a light wooden float valve H which when seated in the lower end of the retaining device seals the same. I also place in the retaining device a heavy ball I, preferably of metal which normally rests upon the light 90 or float valve H thus holding it firmly to its seat. When the bottle is to be emptied it is decanted and the two balls drop into the position shown in Fig. 2 thus permitting passage of liquid around them. If, however, 95 any attempt is made to refill the bottle by submerging it, in an inverted position, the entrance of any liquid into the retaining device will float the light ball H lifting it to its seat and any pressure exerted in an effort to 100 force liquid into the bottle will only cause the said ball H to seat itself more firmly at the conical end of the portion B' of the cylinder B.

Having thus fully described my invention, 105 what I claim as new and desire to secure by Letters Patent, is:—

1. The combination with a bottle having an interiorly recessed neck portion, of a cylinder fitting in said neck portion, said cylinder having a lower conical portion, a spring metal sleeve fitting within the upper portion 110

of the cylinder, the lower portion of said sleeve being of less diameter than the interior diameter of the cylinder, the lower portion of the sleeve being spaced from the cylinder walls, a float valve arranged in the lower portion of the cylinder, a weight valve normally resting on the float valve, the said weight valve being spherical in shape and engaging the lower end of the sleeve, said sleeve forming a stop for said weight valve, means carried by the cylinder for locking the same in the bottle neck, and means carried by the cylinder to prevent tampering with the said valves.

15 2. The combination with a bottle, of a cylinder having a conical contracted lower por-

tion, means for locking said cylinder in the bottle neck, a cage having a solid top carried by the upper portion of the cylinder, a tapering sleeve fitted within the cylinder, the 20 smaller end extending downwardly and being spaced from the sides of the cylinder, a float ball resting loosely in the contracted lower end of the cylinder, and a metal ball resting upon the first mentioned ball, and engaging the smaller end of the sleeve when the bottle is decanted. 25

JAMES H. QUINN.
